UNITED STATES PATENT OFFICE.

FRANCIS B. ABBOTT, OF CHICAGO, ILLINOIS.

IMPROVEMENT IN TRANSPLANTERS.

Specification forming part of Letters Patent No. 146,156, dated January 6, 1874; application filed October 24, 1873.

To all whom it may concern:

Be it known that I, FRANCIS B. ABBOTT, of Chicago, in the county of Cook and State of Illinois, have invented an Improvement in Transplanting-Trowels, of which the following is a specification:

The present invention consists of a sheet-metal blade, which is of suitable size to separate the earth around the roots of plants and flowers, and which is open on one side to be expanded by its flexibility, and compressed by a band, which is moved up and down on the blade by means of a rack and segment lever, so that plants can be removed from the ground in one place and carried to another place for transplanting, as hereinafter fully described and shown.

In the drawing, Figure 1 is an elevation of my improvement in transplanting-trowels; Fig. 2, a vertical section thereof.

A represents a truncated conical sheet-metal blade, which is open on one side and flexible, so as to spring apart and enlarge the horizontal area of the base B. This blade is rigidly attached to a central cap, C, which serves as a means for handling the tool and a support for other parts hereinafter named. A metal ring or clamping-band, D, is placed around the blade A for the purpose of depressing it; and to this ring is rigidly fastened a connecting-bar, E, to which is attached rack E', its shank I extending up through the cap C. A segment-lever, F, is pivoted to the up-

per end of blade A, and arranged, when moved up and down, to raise and lower the rack E, and carry the ring or band D with it, the shank I of the rack being guided by the cap C.

The operation of the device is as follows: The segment-lever F is brought up, as shown in Fig. 2, bringing the band D down on the blade A, so as to lessen the area at its base. The blade is then placed around the roots of a plant, so that the top will project through the opening J in the side of the blade. The latter is then pushed down by the hand to a proper depth, then turned to one side, the earth being used a fulcrum to lift the plant out of its bed. To remove the plant from the blade A, it may be inverted, and the earth wet with water against the blade, so as to be readily removed by bringing the lever F down, as in Fig. 1, enlarging the area of the blade.

I claim and desire to secure by Letters Patent—

1. The combination, in a transplanter, of the blade A, cap C, and band D, as and for the purpose set forth.
2. The combination, in a transplanter, of the blade A, cap C, band D, bar E, rack E', and segment F, substantially as and for the purpose set forth.

FRANCIS B. ABBOTT.
